UNITED STATES PATENT OFFICE.

JOHN E. PERRY, OF SHARON, PENNSYLVANIA, ASSIGNOR TO VALLEY MOULD & IRON CORPORATION, OF SHARPSVILLE, PENNSYLVANIA, A CORPORATION OF NEW YORK.

INGOT MOLD AND STOOL.

Application filed January 18, 1926. Serial No. 81,884.

The present invention relates broadly to metallurgy and more especially to an ingot mold, and a stool therefor.

Heretofore in the art of casting ingots, 5 and more specially steel ingots, vertical ingot molds have been generally of two types, namely, of the big-end-up type and the big-end-down type. In both of these types the side walls of the ingot mold have been 10 tapered to a considerable extent. In the big-end-down type of mold, this tapering of the walls to a large extent has caused in the ingots cast in such molds the zones of cooling to comprise cupped shaped zones 15 with the bottom portion of the cup having a wider cross section than the mouth thereof so that as the metal froze the mouth portions would tend to close up and enclose a volume of molten metal which when finally frozen, 20 left cavities in the middle portion of the ingot as well as a cavity in the upper end of the ingot. These cavities in the lower portion of the ingot are known in the art as "secondary pipes" and the cavity in the 25 upper portion of the ingot is referred to as a "primary pipe". The practical manipulation of equipment makes it desirable to cast the ingots with the big-end-down, even though liabilities of formation of secondary 30 pipes are present. To avoid the difficulties with secondary pipes, etc., the art has gone in some cases to the big-end-up type of mold, in which the metal tends to crystallize in cupped shape zones with the widest part 35 of the cup being the mouth thereof, so that as the metal freezes the secondary piping is generally avoided, although the primary pipe may be slightly larger. Where ingots are cast in a big-end-up type of mold with a 40 heavy taper, the ingot when frozen shrinks and tends to lift the bottom of the ingot upward and to wedge the upper portion of the ingot in the tapered mold. This leaves the lower end of the ingot hanging without 45 an underneath support and this causes cracks which never weld together in subsequent operations.

The present invention, which relates more 50 especially to the art of casting steel ingots, overcomes the difficulties of the known art by providing a mold having a small taper; the maximum of which is considerably less than that heretofore known in the art. I have discovered that a mold in which the

taper, measured by measuring total diameter of the mold relative to the length thereof, is not over one and five tenths percentum produces an ingot in which secondary pipes do not occur when cast big-end-down; and which mold may also be used with equal 60 facilities for casting big-end-up without the attendant defects in ingots of this type.

Where this novel mold is used the disadvantages of the prior art are overcome in that the condition of the steel in the ingot 65 when cast with the big-end-down is that of substantially a solid ingot with the exception of the primary pipe in the top thereof. When this novel mold is used with the big end up, substantially the same result is obtained, because the taper is so slight that there is little difference between ingots cast with big end up or big end down.

Difficulty has also been encountered in the art in connection with open ended molds 75 as to that part of the ingot formed over the stool upon which the mold sets. The present invention also comprises a novel type of stool adapted to cooperate with this narrow taper mold. The stool is provided with 80 a cup which is located with the center of the cup substantially coinciding with the longitudinal axis of the matrix of the mold. This cup in its preferred form is slightly less in diameter than the diameter of the open end 85 of the mold which sets upon the stool, so that a slight marginal flange is formed on the end of the ingot between the cup and the side wall of the ingot mold. This cup forms an extension on the end of the ingot 90 in which extension undesirable dendritic crystallization is obviated, and furthermore, the small ledge between the edge of the cup and the corner of the mold provides a shelf 95 which prevents hot metal from burning out the sharp corner of the mold which sets closely upon the stool to form a metal to metal joint thereby obviating any formation of fins between the stool and the ingot mold.

It is also desirable that the mold and the 100 stool occupy the same relative positions for each set up with the center of the stool being coincident with the longitudinal axis of the mold and therefore guide means may be provided on both the mold and the stool to 105 insure this relation. In view of the fact that this mold is equally adapted for casting ingots either big end up or big end down,

both ends of the mold may be provided with guide means having the same over-all dimensions so that either end of the mold will cooperate with the stool and guides thereon.

- 6 In order to secure the best results, with this mold set-up it is also desirable to provide a hot top structure adapted to cooperate with either end of the mold, and to that end a suitable hot top may be arranged to cooperate with guiding means capable of utilization with either end of the mold so as to position the hot top member on either the big end or the small end of the mold, depending upon which end of the mold is uppermost.

Where the present invention is utilized, namely, the stool, the mold, and the hot top, the difficulties of the prior art as herein specified are overcome, and the ingot resulting therefrom is one which is of a better internal structure from the standpoint of steel, and a better external structure from the standpoint of subsequent manipulation than the ingots of the known prior art.

- 25 Realizing that the present inventions may be embodied in structures other than those specifically disclosed herewith, it is to be understood that the disclosure herein is illustrative and not to be considered in the limit-
30 ing sense.

Other and further objects of the present invention will in part be obvious and will in part be pointed out hereinafter in the specification following by reference to the accompanying drawings forming a part thereof, and throughout which like characters are used to represent like parts.

- Fig. 1 is an elevational sectional view illustrating a preferred form of stool, a preferred 40 form of the mold showing a big-end-up set-up and a hot top structure adapted to cooperate with the mold.

Fig. 2 is a plan view of the stool showing the bottom of the mold in cross section.

- 45 Referring now more specially to Figs. 1 and 2, the stool which preferably is made of cast iron, is provided with a cupped shaped recess 1 having a substantially flat central portion 2 and rounded side walls 3. The 50 central or bottom 2 of this recess 1 is substantially a flat surface and the rounded side walls 3 have a curvature which is formed with a radius that is substantially equal to the depth of the recess. This arrangement 55 provides a recess which is deep and wide so as to form a splash pool in which the splashes of molten steel during pouring tend to drop on the surface of the flat pool and not to splash against the sides of the mold 60 or the top of the stool. The substantially vertical side walls of this recess prevent slopping over of the molten steel until the pool has completely filled, at which time the steel quickly overflows the pool and comes 65 into contact with the side walls of the mold.

This construction forms an excellent end on the ingot without the formation of a scale which would sprawl off during rolling as would be the case where the central pool is so small to permit drops to splash over and fall upon a flat cold surface on the stool. The stool adjacent said cup preferably comprises a substantially flat seat 5 to support a suitable ingot mold and guiding ears 6 are provided to cooperate with suitable portions 75 on the mold in order to position the central part of the recess 1 substantially coincident with the longitudinal axis of the matrix of the mold. The mold preferably comprises a body portion 7 of cast iron, and which may be provided on each end with lifting lugs 8, the sides of which are formed to cooperate with the guiding ears 6 on the stool as is illustrated in Fig. 2, to definitely position the bottom of the mold upon the flat seat 5 of 80 the stool. In view of the fact that this mold may be used with either end up the dimensions of the guiding surfaces on the lugs 8 are the same on each end of the mold. The ends of the mold preferably are provided with openings 9 which may receive holding pins or keys 10 which may be utilized to position a suitable hot top 11 upon either end of the ingot mold, dependent upon which end of the mold is used as the mouth thereof. One feature of prime importance of the present invention is the degree of taper of the matrix side walls of the mold and I have discovered that the maximum limit for this taper shall not exceed one and five tenths percentum, total taper; that is, if the ingot mold is 70 inches long, of a rectangular cross-section matrix, I have found that the measurement of approximately nineteen inches for each dimension of the rectangle at the small end of the mold should carry a measurement of substantially twenty inches at the large end of the mold as a maximum limit, or in other words one inch taper in seventy inches in length. The minimum limit is determined by the clearance necessary to strip the ingot from the mold and this is somewhat dependent upon the accuracy with which longitudinal lines or planes on the interior surface of the matrix approach a theoretical straight line or plane.

Having thus described my invention, what I claim is:

1. As an article of manufacture, an ingot mold comprising an integral body portion with the matrix thereof having a taper not to exceed one and one half percent.
2. As an article of manufacture, a vertical ingot mold for steel ingots comprising an integral body portion of cast iron with the matrix thereof having a taper not to exceed one and one half percent.
3. As an article of manufacture, a one piece ingot mold of cast iron with the matrix

walls thereof tapered to an amount of substantially one inch in cross section to seventy inches in length.

4. In the art of casting steel ingots, a mold set-up having the matrix thereof constructed to provide a vertical cavity with the side walls thereof having a taper not to exceed one and one-half per cent with the bottom of said cavity comprising a recess having rounded side walls and a substantially flat bottom and with an annular shoulder between said recess and said vertical side walls.

5. As an article of manufacture, an ingot mold provided with an open ended matrix with the side walls of said matrix having a maximum taper of one and one half per cent, and with the ends of said ingot mold finished in such manner that either end thereof is adapted to cooperate with a suitable stool.

6. As an article of manufacture, a stool for ingot molds, said stool comprising a body portion of cast iron, and having a recess

therein having a substantially flat bottom 25 surface terminating in curved sides having a radius of curvature substantially equal to the depth of the recess adapted to comprise a part of the matrix wall of the mold set up and to form a rounded end on the ingot. 30

7. As an article of manufacture, a stool for ingot molds, said stool comprising a body portion of cast iron, and having a recess therein having a bottom surface terminating in curved sides having a radius substantially 35 equal to the depth of the recess and adapted to comprise a part of the matrix wall of the mold set up and to form a rounded end on the ingot, and a mold seat on said stool adapted to form a metal to metal joint with 40 a suitable mold.

8. An ingot mold for casting steel ingots and having an ingot forming chamber with substantially flat walls tapering upwardly and outwardly with a portion of said walls 45 having a taper not to exceed one and one half per cent.

JOHN E. PERRY.
